Primary Examiner — Mitchell I. Siegel(74) *Attorney, Agent, or Firm* — Muncy, Geissler, Olds & Lowe, P.C.(57) **CLAIM**

The ornamental design for a roller coaster track section, as shown and described.

DESCRIPTION

FIG. 1 is a perspective view of a first embodiment of a roller coaster track section, showing my new design;
 FIG. 2 is a top plan view thereof;
 FIG. 3 is a front elevational view thereof, the rear elevational view being a mirror image thereof;
 FIG. 4 is a perspective view of a second embodiment of a roller coaster track section, showing my new design;
 FIG. 5 is a top plan view thereof; and,
 FIG. 6 is a front elevational view thereof, the rear elevational view being a mirror image thereof.

1 Claim, 6 Drawing Sheets(56)
